WILLIAM D. ROEDER, OF DWIGHT, ILLINOIS.

FOUNTAIN PEN.

Application filed March 19, 1926. Serial No. 95,851.

These improvements relate to fountain pens and have for their prime object the provision of a notably simple, easily operated, cheap and satisfactory fountain pen device.

The present improvements have a more specific relation to means for charging a fountain pen device with ink, and are in that class of fountain pen structures in which piston pump means are provided. It is not new to provide a piston cooperating with the shell or barrel for drawing ink into the hollow interior of the device, nor to provide a hollow piston for the purpose.

In such constructions, speaking generally, a problem arises as to the disposition of air during the pumping operation and in the provision of means for preventing an undue flow of ink at the pen point due to the presence of an excess of air within the pen chamber during the writing operation. Such difficulties have been sought to be overcome in various ways including automatically-operating valves variously disposed within the device, such valves becoming clogged with ink and for various other reasons proving unsatisfactory.

It has also been suggested to have the operator apply a finger to an air duct in the hollow plunger to provide the desired partial vacuum, the removal of the finger permitting air to escape on the inward stroke of the plunger, with means for sealing such vent opening when the device is in use, which construction results in soiling the finger of the operator, a coating of ink on the outside of the plunger, and still other objections.

It is an object to overcome all such disadvantages, and by simple means.

In the drawings Figure 1 is a longitudinal section through the pen complete, except for the front end portion, showing the several parts of the device in their normal relative positions when the device is in condition for use; Fig. 2 is a similar section of the same parts, omitting the outer cap, showing the piston partly withdrawn, as in the act of filling the pen; and Fig. 3 is an enlarged section through the front end portion and through the filler duct or tube.

The tubular shell or casing 10 illustrated in the drawings may be of metal, hard rubber, etc. in accordance with ordinary practice. Threaded into its forward end is a

head or nozzle member 11 which, as shown by Fig. 3, is cylindrically bored and provided with a tightly-fitting plug 12, cylindrical in form and extending beyond the head 11, with recess provisions between it and the head 11 for receiving the pen point 13. A duct 14 leads from the hollow interior 15 of the casing to the under surface of the pen point 13. There is nothing peculiar about the construction of the shell or casing 10, the head 11, the pen point 13 and the plug 12 as thus far described, and the only departure at the front end to be noted is in the provision of the duct 15 leading from the inner end of the head 11 to the outer end of the plug 12, the duct 15 opening at 15^a. The present improvements may be applied to pen constructions of various details at the normally front end.

Within the cylindrical shell or casing 10 there is a hollow plunger 16, which may be a piece of metal pipe, hard rubber, etc. Spaced collars 17 are shown at its inner open-end portion between which is packing material 18, thus forming a packed piston head having a good interfitting sliding engagement with the cylindrical hollow interior 15 of the shell. The body of the tubular piston 16 passes with a nice sliding fit through a circular constricted opening in the nipple-like extension 19 of the barrel 10. The outer end 20 of the piston tube 16 is closed as by a plate soldered thereat, and axially extending from this fixed closure 20 is a small pin 21 passing through a constricted opening in a small cap 22 having an internal thread at 23 adapted to engage an external thread on the nipple-like part 19 of the casing. A head 24 on the pin 21 provides a swiveled connection between the cap 22 and the piston as a whole.

Extending from the duct 15 (Fig. 3) is a small pipe 25 which, as will be observed from Figs. 1 and 2, extends into the hollow interior of the piston, and (Fig. 1) reaches almost to the end of the closure 20 at the outer end of the piston when the parts are in their normal relations for use. Between this closure 20 and the end of the tube 25 is positioned a packing element 26, which may be of soft rubber, cork or similar material, and which is adapted to close the open end of the tube 25 when the small cap 22 is threaded upon the nipple 19. This tube 25 is securely fixed to the head 11, as by frictionally forc-

ing its outer end into an enlargement of the duct 15 whereby a continuous duct is provided from the opening at 15^a to the inner end of the tube 25.

5 The cap 27 is shown as an ordinary element of fountain pen construction adapted to fit upon the rear end of the barrel to extend its length for writing purposes, and upon the front end to cover the pen point 10 when the device is not in use.

The operation of the device is as follows: The outer cap 27 being laid aside, the smaller cap 22 is unscrewed from the nipple 19, thus freeing the piston for pumping action, and this cap 22 then becomes a finger piece for operating the piston. The pen point is dipped into a supply of ink so that the opening at 15^a is covered. In most instances it will be preferable also to dip the pen deeply 20 enough to cover a portion of the end part 11^a of the head 11 to exclude outer air from the duct 14. The piston is then drawn outwardly, creating a partial vacuum which draws ink into the hollow interior 15 through both the ducts 14 and 15.

While the piston 16 may be long enough to extend to the head 11, whereby a single withdrawal of the piston would charge the hollow interior to completion, and even with 30 an excess amount of ink, I prefer to have the piston considerably shorter than the length of the barrel, both to avoid charging with an excess which would have to be forced out, and to give the barrel somewhat greater capacity since the space at 28 surrounding the hollow piston stem 16 is normally free of ink.

With the piston thus shortened the pen 40 may be filled on one stroke or one or more additional pumping strokes may be required, according to the relative length and diameter of the pump parts. Should the first outward stroke not fill the hollow interior, on the return stroke the air displaced by the inward movement passes forward through the tube 25 and out of the opening 15^a. The pen does not need to be withdrawn from the ink on the return stroke as the bubbling 50 of the ink in the supply does no harm. On the second pumping stroke more ink is drawn into the hollow interior as before. A third pumping stroke may be employed if made necessary by a particular construction; but at any time that the pen is filled 55 the return stroke results merely in forcing excess ink out through the ducts 14 and 15.

The cap 22 is then threaded back upon the nipple 19, thus sealing the inner open end of the small pipe 25 by the packing or stoppage 60 26. It is thereupon impossible for air to enter the hollow interior 15 through the duct 15 and pipe 25, so that the feeding of the ink will depend upon that small amount of air which enters the hollow interior 65 through the feeder duct 14, or, in any other

specific construction, upon the provisions made for controlling the feed to the pen proper.

In practice the operator will dip the front end of the device into the ink supply and 70 work the pump once and probably then another time for good measure. When an excess needs to be forced out, the pipe 25 will remain filled with ink. This would not be a real objection since the sealing of the 75 inner end of the pipe prevents its discharge through the opening 15^a. However, the pipe 25 and duct 15 may be cleared of ink by lifting the pen out of the supply, drawing back the plunger slightly, sucking the ink 80 in these duct means 15 and 25 into the hollow interior of the device, whereupon, on the final return stroke a little ink may issue through the port 14 and only air or air and ink will pass forward through the 85 pipe 25. This operation may be repeated.

The duct 15-25 is the principal passage-way for both intake and discharge since the duct 14 is fairly well closed by the pen proper.

I contemplate as being included in these improvements such changes, departures and variations from what is herein specifically illustrated and described as fall within the scope of the appended claims.

I claim:

1. In a fountain pen, the combination of a tubular casing, means at one end thereof for holding a pen proper in communication with the hollow interior of the casing, piston pump means within the casing for drawing ink into the hollow interior of the casing, a cap threaded upon the outer end of the casing, a swivel connection between said cap and said piston pump means providing an intake duct for ink leading from the end portion of the device adjacent to the pen proper and extending into the hollow interior of the casing, and means carried by the pump means for sealing the inner end of said duct when the several parts of the device are in their normal relations for use.

2. In a fountain pen, the combination of a tubular casing, means at one end thereof for holding a pen proper in communication with the hollow interior of the casing, tubular piston pump means within the casing for drawing ink into the hollow interior of the casing, a finger piece swivelled to the outer end of said pump means, means for holding the finger piece upon the casing, means providing an intake duct for ink leading from the end portion of the device adjacent to the pen proper and extending into the hollow interior of the pump means, and means for sealing the inner end of said duct when the several parts of the device are in their normal relations for use, said last-mentioned means being carried by the pis-

ton and engaging the inner end of said duct on the inward stroke of the piston.

3. In a fountain pen, the combination of a tubular casing, means at one end thereof for holding a pen proper in communication with the hollow interior of the casing, a tubular piston having an open inner end and coacting with the casing to provide pump means for drawing ink into the hollow interior of the casing, means providing an intake duct for ink leading from the end portion of the device adjacent to the pen proper and extending into the open end of the hollow piston, and means for sealing the inner end of said duct when the device is normally in condition for use.

4. In a fountain pen, the combination of a tubular casing, means at one end thereof for holding a pen proper in communication with the hollow interior of the casing, a tubular piston having an open inner end and coacting with the casing to provide pump means for drawing ink into the hollow interior of the casing, means providing an intake duct for ink leading from the end portion of the device adjacent to the pen proper and extending into the open end of the hollow piston, and means for closing the inner end of said duct when the device is normally in condition for use, said last-mentioned means comprising a soft, cushion-like stopper carried by the piston and engaging the inner end of the duct on the inward stroke of the piston.

5. In a fountain pen, the combination of a tubular casing, means at its forward end for holding a pen proper, a tubular piston having an open inner end and a closed outer end and coacting with the casing to provide pump means for drawing ink into the hollow interior of the casing, a feeder for ink extending forward from the casing and underlying the pen proper, said feeder having a duct for feeding ink to the pen proper from the interior of the casing, said feeder having an intake duct for ink leading from near the free end portion of the feeder normally adjacent to the pen proper and extending to the interior of the casing, and a tube extending from said last mentioned duct into the open end of the hollow piston, and means carried by the piston at its

outer end portion for sealing the free end of said tube when the device is normally in condition for use.

6. In a fountain pen, the combination of a tubular casing, means at one end thereof for holding a pen proper in communication with the hollow interior of the casing, a feeder normally adjacent to the pen proper and extending forward from the end of the casing, a tubular piston having an open inner end and a closed outer end and coacting with the casing to provide pump means for drawing ink into the hollow interior of the casing, means providing an intake duct for ink leading from near the free end of the feeder adjacent to the pen proper and extending into the open end of the hollow piston and to a place adjacent to the outer end of the piston when the piston is at the end of its inward stroke, means within the piston and at its outer end for sealing the inner end of said duct when the piston is at the end of its inward stroke, and means for securing the piston in fixed relation to the casing with the piston at the end of its inward stroke.

7. In a fountain pen, the combination of a tubular casing, means at one end thereof for holding a pen proper in communication with the hollow interior of the casing, a tubular piston having an open inner end and a closed outer end and coacting with the casing to provide pump means for drawing ink into the hollow interior of the casing, means providing an intake duct for ink leading from the end portion of the device adjacent to the pen proper and extending into the open end of the hollow piston and to a place adjacent to the outer end of the piston when the piston is at the end of its inward stroke, means within the piston and at its outer end for sealing the inner end of said duct when the piston is at the end of its inward stroke, and means for securing the piston in fixed relation to the casing with the piston at the end of its inward stroke, said last-mentioned means including a finger-piece swiveled to the piston, said finger-piece and the casing having coacting screw threads.
